United States Patent Office.

GEORGE E. WEST AND WILLIAM R. CUNNINGHAM, OF LAFAYETTE, INDIANA.

Letters Patent No. 70,055, dated October 22, 1867.

IMPROVED CARPET-FASTENER.

The Schedule referred to in these Letters Patent and making part of the same.

TO ALL WHOM IT MAY CONCERN:

Be it known that we, GEORGE E. WEST and WILLIAM R. CUNNINGHAM, of Lafayette, in the county of Tippecanoe, and State of Indiana, have invented new and useful improvements in the Mode of Fastening Carpets; and we do hereby declare that the following is a full, clear, and exact description thereof, reference being had to the accompanying drawing, making part of this specification, in which—

Figure 1 is a front elevation of a section of the base-board of a room, with our device for fastening the carpet thereto attached.

Figure 2 is a transverse section of the same.

Figure 3 is a transverse section of the device as it may be applied when putting down the base in new houses.

Similar letters of reference indicate corresponding parts in the several figures.

To enable others skilled in the art to make and use our invention, we will proceed to describe its construction and operation.

A represents the ordinary base-board used in buildings, F is the floor, and E the carpet.

Our improvement consists in attaching a narrow strip of board, C, to the base A, say three or four inches from the floor. The strip C may be moulded in any desired ornamental pattern. To the lower edge of strip C another narrow strip of board, B, is hinged, as shown at G. This strip extends down to near the floor, leaving merely the space between them required for the thickness of the carpet, and this should be such that when the strip B is in the position to fasten the carpet as shown it will press the latter firmly to the floor. The rear bottom edge of strip B is bevelled as shown, and a strip or tongue of hoop iron, D, is set at an angle in a kerf cut in the strip as shown. This strip of iron may have notches, if desired, cut at intervals along its lower edge, somewhat like saw-teeth, so that it will hold the carpet more effectively.

In putting down the base in new houses the strip B may be attached directly to the base A, as shown in fig. 3, omitting the strip C, the latter being essential only when the device is applied in houses already built, as shown in figs. 1 and 2. We prefer, however, attaching our device to the base by means of the strip C, setting the base an inch or two from the floor, as in fig. 3, to form a recess, I, to receive whatever surplus of the edge of the carpet may be taken up in the process of stretching it. The appearance of the device thus attached would not be objectionable, and, besides, it affords a convenient and practicable mode of adjusting the device to the floor when the shrinking of the floor timbers makes it necessary to do so, in which event the strip C may be taken off and set down to the proper position. In houses already built the front lower edge of the base is generally rabbeted, as shown in fig. 2, to set into the shoe or carpet strip which is usually nailed to the floor to make a finish, and in applying our device in such cases this rabbet forms the recess, I, to receive the edge of the carpet.

The strip B may be made in sections of any desired or convenient length, and may be hinged to the strip C or base A with any style of hinge, or in any manner to make the hinges least conspicuous. When the carpet is to be put down the strips B are turned up, so that the edge of the carpet may be put under it and within reach of the iron strip or tongue D. The strip B is then turned down and pressed back against the base A, which stretches the carpet evenly and tightly, and at the same time clamps it firmly between the lower edge of strip B and the floor.

The advantages of this mode of fastening carpets are that they are more easily and expeditiously put down or taken up; the strip B pressing firmly down upon it prevents the collection and accumulation of dirt around the edges, as in other modes; it is not frayed or injured by driving or drawing the tacks; and by the act of fastening it is more evenly stretched at the edges, and is also more firmly held. The strips B may be fastened with screws as shown, or spring hooks H may be driven into the base and project through mortises in the strips to hold them, as shown in fig. 3.

Having thus fully described our invention, what we claim as new, and desire to secure by Letters Patent, is—

The combination of the strips B and C with the tongue D, all arranged with the base A, as described, for the purpose specified.

GEORGE E. WEST,
WILLIAM R. CUNNINGHAM.
